Attorney

UNITED STATES PATENT OFFICE.

ROBERT L. CUZEN, OF PLAINFIELD, NEW JERSEY.

PHONOGRAPH-LAMP ATTACHMENT.

1,343,767.

Specification of Letters Patent. Patented June 15, 1920.

Application filed September 10, 1917. Serial No. 190,634.

To all whom it may concern:

Be it known that I, ROBERT L. CUZEN, a citizen of the United States, residing at Plainfield, in the county of Union and State 5 of New Jersey, have invented certain new and useful Improvements in Phonograph-Lamp Attachments, of which the following is a specification.

This invention relates to phonographs and 10 it is the principal object of the invention to provide a novel lamp attachment for the sound box thereof whereby the light rays emitted by the lamp will be projected onto the first or start of the sound recording 15 grooves occurring on a record, thus, enabling the user to accurately position the sound box when starting the machine.

Among other aims and objects of the invention may be recited, the provision of an 20 attachment of the character mentioned with a view to compactness, and in which the 25 number of parts are few, the construction simple, the cost of production small, and efficiency and operation high.

The improvements in the details and arrangement of parts will be apparent from 30 an inspection of the accompanying drawings, in connection with the specific description hereinafter contained, and wherein the 35 preferred embodiment of the invention is illustrated for the purpose of imparting a full understanding of the same.

In the drawings:

Figure 1 is a detail in perspective of a 35 phonograph sound box and a fragment of the tone arm having the improved lamp attachment applied thereto;

Fig. 2 is a vertical section taken through the tone arm showing the arrangement of 40 the attachment thereon; and

Fig. 3 is a vertical longitudinal section taken through the lamp attachment.

Having more particular reference to the drawings, T represents the tone arm of the 45 phonograph having the usual sound box S pivotally supported thereon as at p.

With more particular reference to the present improvements, the attachment includes a substantially U-shaped bracket 1 50 preferably formed of spring metal and adapted to be arranged about the lower portion of the tone arm T, as shown in the Fig. 1. A screw threaded electric lamp socket 2 is carried by the U-shaped bracket 55 1, the said socket being provided with a base 4 in which the usual contact terminal

5 is arranged, whereby one connection may be made with the plug of an electric lamp 6 which is turned into engagement with the said socket. In this connection, it is to be 60 noted that the incandescent lamp and its respective socket are arranged at such an angle when positioned upon the under side of the tone arm T as to cause the projection of the light rays diagonally downward to 65 a point adjacent the needle of the sound box S, thus enabling the user to easily discern the first or start of the sound recording grooves occurring on a record, in order that the needle of the said box may be accurately 70 engaged or placed therein.

A cap 7 is arranged over the open rear end of the screw threaded lamp socket 2 and is provided with an opening through which an electrical conductor 8 is passed 75 into engagement with the contact terminal 5. A second electrical conductor 8' is also provided and extends into engagement with a contact terminal 9 arranged upon the under side of a switch arm 10 preferably 80 formed of spring metal which is secured to the underside of a split insulating band 3 at a point opposite the connection of the bracket 1 with the socket 2 and has a portion thereof arranged adjacent one side of 85 the bracket 1. Thus, by engaging that portion of the switch arm as adjacent the bracket with the same, a circuit will be closed through the electrical conductors 8 and 8' and the incandescent lamp 6, thereby 90 lighting the same. It will be readily understood, that but one hand will be required to properly place the needle of the sound box S and close the circuit through the incandescent lamp 6; one finger of the user's 95 hand being extended into engagement with the said switch arm 10 in order that the same may be moved into engagement with the adjacent side of the bracket 1. Just as soon as the sound box needle is properly 100 positioned and the hand is released from the tone arm, the circuit through the electrical conductors and the lamp 6 will be broken, due to the inherent resiliency of the circuit closing arm 10.

Manifestly, the construction shown is capable of considerable modification and such modification as is within the scope of my claim, I consider within the spirit of my invention.

I claim:

An attachment of the character described

including an electric lamp socket, an insulating band secured thereto, a substantially **U**-shaped spring bracket attachable to the tone arm of a phonograph and having 5 the web portion secured to the socket, a lamp fitted in the socket, and a substantially **L**-shaped spring circuit closing arm secured at one end to the insulator at a point

diametrically opposite the bracket and having its opposite terminal extended vertically 10 in proximity to and movable into contact with one of the arms of the **U**-shaped bracket.

In testimony whereof I affix my signature hereto.

ROBERT L. CUZEN.
